(57) **CLAIM**

The ornamental design for an ankle protector as shown and described.

DESCRIPTION

FIG. 1 is a front perspective view of an ankle protector showing the new design;

FIG. 2 is a rear perspective view thereof;

FIG. 3 is an exploded rear perspective view thereof;

FIG. 4 is a front elevation view thereof;

FIG. 5 is a rear elevation view thereof;

FIG. 6 is a left side elevation view thereof;

FIG. 7 is a right side elevation view thereof;

FIG. 8 is a top plan view thereof;

FIG. 9 is a bottom plan view thereof; and,

FIG. 10 is a cross-section side view thereof, taken along line 10-10 of FIG. 4.

The broken lines depict portions of the ankle protector that form no part of the claimed design.
